UNITED STATES PATENT OFFICE.

JOHN HEIBECK, OF HOUSTON, TEXAS.

WHEEL.

1,004,023.

Specification of Letters Patent. Patented Sept. 26, 1911.

Application filed November 4, 1909. Serial No. 526,245.

To all whom it may concern:

Be it known that I, JOHN HEIBECK, a citizen of the United States, residing at Houston, in the county of Harris and State of Texas, have invented certain new and useful 5 Improvements in Wheels, of which the following is a specification.

My invention relates to new and useful 10 improvements in wheels, and more particularly in that class of wheels designed with special reference for use on barrows and trucks.

The object of the invention is to provide 15 a wheel of the character described that will at once be strong and light and will be capable of withstanding an unusual amount of strain in proportion to the amount of material therein.

Another feature resides in the provision 20 of a novelly constructed hub which is contrived with special reference to the attainment of great strength.

A further feature of the invention resides in the provision of an internal oil 25 chamber, within the hub, arranged for the purpose of automatically oiling the hub bearings.

With the above and other objects in view 30 my invention has particular relation to certain novel features of construction and arrangement of parts, an example of which is given in this specification and illustrated in the accompanying drawings, wherein:—

Figure 1 is a side elevation of the wheel, 35 and Fig. 2 is a vertical diametrical sectional view thereof.

Referring now more particularly to the drawings, wherein like numerals of reference designate similar parts in each of the 40 figures, the numeral 1 refers to a circular metallic disk or plate which comprises the main body of the wheel. This plate has a central opening of a size sufficient to provide for the hub and is also provided with a 45 series of openings 2, alined concentric with the central opening and of such a size as to make the wheel as light as possible consistent with the desired strength thereof.

For a rim or felly of the wheel I have 50 provided two angle irons 3 and 4 which have been formed in a circular shape, as shown in the figures, and secured to the periphery of plate 1 in the manner presently to be described:—The said angle irons have first 55 been formed so that one of the webs of each will be parallel to the axial line of the wheel

and the other web will be perpendicular thereto, and the two irons are then secured to the outer edge of the circular plate 1, in such a manner that the said parallel webs 60 will be in exact alinement with each other, and the perpendicular webs will embrace the outer edge of said plate, as shown in Fig. 2, the periphery of the plate being flush with the periphery of the angle irons. 65

A plurality of bolts or rivets 5 are then passed through the inner webs and the plate, at suitable distances apart and in this manner the angle irons are forced to closely clamp the plate, and their outer webs form 70 a rim for the wheel.

In order to strengthen the joint formed by the meeting of the ends of the angle irons 75 3 and 4 I have secured upon the inner sides of the outer webs short plates 6, which are riveted to said webs and which bind said joints.

In the formation of the hub of the wheel I have provided conical shaped castings 7 and 8 the faces of which are designed to rest 80 against the inner edge of plate 1, and surround the central opening thereof. The apexes of these castings are prolonged into cylindrical shaped bearing members 9 and 10. In order to secure the members 7 and 85 8 in their proper position I have provided conical shaped collars 11 and 12, of a size sufficient to fit snugly over the castings 7 and 8 respectively. The bases of these collars are prolonged into circular flanges 13 90 and 14 which embrace plate 1 from opposite sides and are secured thereto by means of rivets 15 which pass through the flanges and the plate. The apexes of the collars are also prolonged into cylindrical shaped flanges 16 95 and 17 which closely surround members 9 and 10 respectively. The angle which the sloping sides of the castings 7 and 8 and collars 11 and 12 bear to the plate 1 and the axial line of the wheel may be varied in 100 order to give the desired strength. The arch effect which this construction gives to the hub will be found to impart great strength thereto and thus preserve the wheel 105 against warping.

As is readily obvious the hub is provided with an internal chamber 18. I have made provision whereby this chamber may be utilized for the purpose of oiling the bearings of the wheel. A small orifice passes through collar 11 and casting 7 and communicates with chamber 18. This orifice is provided

for the purpose of admitting a lubricant to the said chamber, which is partially filled with the lubricant, and as the wheel turns a portion of this lubricant is carried around upon the inner walls of the chamber and gradually runs down said walls onto shaft 20, which passes axially through the bearing members 9 and 10, and works outwardly along the shaft and keeps the bearings 10 oiled.

A wheel constructed in accordance with the foregoing description and the drawings accompanying the same, and made a part thereof, will be found to be easily and cheaply constructed, automatically oiled in 15 its bearings, and will further possess lightness and durability the two prime virtues sought to be attained.

What I claim is:—

20 In a wheel of the character described, a

hub comprising a disk having a central opening therethrough, two opposing cone shaped members whose bases rest against said disk on opposite sides and surround said central opening, said cone shaped members having their bases concaved so as to leave a central chamber within said hub, bearing members integral with said cone shaped members and continuing from the apexes thereof, similar cone shaped collars 25 fitting over said cone shaped members and means for securing the said collars to the disk.

In testimony whereof I have signed my name to this specification in the presence of 35 two subscribing witnesses.

JOHN HEIBECK.
